UNITED STATES PATENT OFFICE.

GEORGE ARTHUR RUDD, OF TORONTO, ONTARIO, CANADA.

HORSE-COLLAR.

1,176,249.

Specification of Letters Patent. Patented Mar. 21, 1916.

Application filed August 2, 1915. Serial No. 43,229.

To all whom it may concern:

Be it known that I, GEORGE A. RUDD, a subject of the King of Great Britain, residing in the city of Toronto, county of 5 York, Province of Ontario, Canada, have invented certain new and useful Improvements in Horse-Collars, of which the following is a specification.

This invention relates to means adaptable 10 for use with either long or short straw collars to produce a depression at the throat to relieve pressure on the horse's windpipe. My aim is to provide for this purpose means which may be readily applied either during 15 or after the construction of the rest of the collar which will effectively produce the effect desired and in a permanent manner.

I attain my object by providing a plate 20 which is bent to the desired shape either before or during the manufacture of the collar and which is suitably secured to the casing of the collar to hold the latter in the desired shape.

The specific preferred arrangement of the 25 plate and the securing means are herein-after more specifically described and illustrated in the accompanying drawings in which—

Figure 1 is a front view of a horse collar 30 provided with my improvements; Fig. 2 an enlarged cross section through the throat portion of a collar provided with my improvements; Fig. 3 a detail partly in section showing the lower plate of the attachment in front elevation; Fig. 4 a plan view of the plate of the connecting clip; Fig. 5 a plan view of the lower plate of the attachments; and Fig. 6 a perspective view of the seam covering plate of the attachment.

In the drawings like numerals of reference indicate corresponding parts in the different figures.

The horse collar is in its main features of 45 ordinary construction, 1 being the rim and 2 the body, the usual groove for the hames being formed exteriorly between the two. It will be noted particularly on reference to Figs. 1 and 2 that at the center of the 50 throat portion of the collar a marked depression is formed. This depression is caused and is maintained by means of the attachments I will now describe.

4 is a plate suitably curved to give the required dip. This plate is secured in place either inside or outside the casing of the

collar at the outer side of the throat portion. The plate is shown as applied to the exterior surface of the casing in the drawings and is fitted in the groove between the 60 rim and throat. This plate 4 is suitably secured in place preferably by through fastenings. A preferred construction is shown in the drawings comprising a plate 3 fitted to the inner surface of the throat, and a clip 65 comprising the plate 5 and the bolts 6. The plate 4 is provided with the lugs 7 preferably, though not necessarily, formed as part of a separate clip 9 fitted to the plate 4, which is preferably an L-angle in 70 cross section. The bolts 6 pass through the plate 5, the plate 3 and the collar and are set up on the lugs 7 by means of suitable nuts 8. The bolts are preferably pointed to enable them to be forced through the 75 collar.

The plates 4 and 5 which are chiefly instrumental in the shaping of the collar are thus securely held in position relative to one another, and the dip in the throat of the 80 collar is thus formed and maintained. As the plate 3, which is of thin flexible material, may be carried well around the front of the rim 1 as shown, the collar may be formed with a seam at the throat which 85 makes the collar much easier and cheaper to make. The plate 3 may, however, be dispensed with if the collar is not secured at the throat or if the appearance of the seam is not objectionable. The plate 4, being 90 drawn close up into the groove between the rim and the body, does not interfere in any way with the attachment of the hames, and the presence of the projecting lugs on the clip 9 serves to prevent the hames fastening 95 slipping out.

It will be understood of course that various changes may be made in the details of construction without departing from the spirit of my invention, one of the principal 100 features of which is the securing of a shaping plate in a position at the throat of the collar to give the required dip therein and the drawing of the stuffed casing of the collar to the shape of the plate.

105 What I claim as my invention is:

1. A stuffed horse collar with a flexible casing having a narrow curved metal plate applied to the outside of the casing at the outer side of the throat between the rim and 110 throat of the collar and shaped to produce a depression extending transversely of the

casing to relieve pressure on the windpipe of a horse wearing the collar; a narrow plate applied to the inner side of the casing and shaped to coöperate with the metal 5 plate to form said depression; and connections passing through the collar connecting the plates together at the middle of the throat portion of the collar.

2. A horse collar having a curved plate 10 applied to the outside of the casing at the outer side of the throat of the collar and shaped to produce a depression to relieve pressure on the windpipe of a horse wearing the collar; a curved plate applied to the 15 outside of the casing at the inner side of the throat portion of the collar; a clip for connecting the two plates comprising a plate adapted to fit the second mentioned plate

and provided with bolts adapted to pass through the collar; and lugs for the second mentioned plate on which the said bolts may be set up. 20

3. A horse collar flexible at the throat and having a curved plate applied exteriorly thereto and shaped to produce a depression to relieve pressure on the windpipe of the horse; and fastenings extending through the collar securing said plate in place comprising pointed bolts and nuts therefor. 25

Signed at Toronto, Canada, this 29th day 30 of July 1915, in the presence of the two undersigned witnesses.

GEORGE ARTHUR RUDD.
